(57) **CLAIM**

We claim the ornamental design for an adjustable vehicular holder for an electronic or air freshener device, as shown and described.

DESCRIPTION

FIG. 1 is a top perspective view showing an adjustable vehicular holder for an electronic or air freshener device of our new design, in a nut-fully engaged and a leg-clamped first position;

FIG. 2 is a bottom perspective view thereof, in the first position;

FIG. 3 is a side elevational view thereof, in the first position, with an opposite side elevational view being a mirrored image thereof;

FIG. 4 is a side elevational view, in the first position, taken perpendicular to that of FIG. 3, with an opposite side elevational view being a mirrored image thereof;

FIG. 5 is a top plan view thereof, in the first position;

FIG. 6 is a bottom plan view thereof, in the first position;

FIG. 7 is a top perspective view showing the adjustable vehicular holder for the electronic or air freshener device, in a nut-partially engaged and a leg- open second position;

FIG. 8 is a side elevational view thereof, in the second position, with an opposite side elevational view being a mirrored image thereof;

FIG. 9 is a side elevational view thereof, in the second position, with an opposite side elevational view being a mirrored image thereof;

FIG. 10 is a top plan view thereof, in the second position; and,

FIG. 11 is a bottom plan view thereof, in the second position.
